HEAT PUMP

Edward L. Garfield, Lutz, Fla., assignor to Typhoon Prop-R-Temp Corporation of Florida, Tampa, Fla., a corporation of Florida

Application August 26, 1953, Serial No. 376,688

5 Claims. (Cl. 62—129)

The present invention relates to a heat pump, that is, to a refrigeration machine in which the refrigerant flow is reversible whereby the machine may be used both for cooling and for heating.

More particularly still the invention relates to a heat pump which employs the usual compressor but which has a novel gaseous heat exchanger as well as a novel liquid heat exchanger. Each of these heat exchangers is highly efficient by itself and, used together, the combination produces a heat pump with extremely great efficiency.

The gaseous heat exchanger serves as an evaporator during the cooling function and as a condenser during the heating function and has been termed a gaseous heat exchanger because of the fact that the air flowing over this device is cooled or heated.

The liquid heat exchanger serves as a condenser during the cooling function and as an evaporator during the heating function and has been termed a liquid heat exchanger because in it the refrigerant is in heat exchange relationship with cooling or heating water.

The gaseous heat exchanger or evaporator-condenser comprises a coil or plurality of coils connected in parallel relationship and formed into an hourglass form providing a heat exchanger which eliminates the usual return bends and is therefore very economically constructed.

The liquid heat exchanger comprises a plurality of small diameter tubes located within a larger diameter tube and having refrigerant medium circulating within the smaller tubes and water in the space within the large tube, surrounding the smaller tubes. In the past, a similar arrangement has been utilized wherein, however, the refrigerating medium circulated within the large tube and water within the small interior tubes, but this has proven unsatisfactory for use in a heat pump due to the freezing of water within the small tubes.

When the two units generally described above are utilized in a heat pump together with capillary tubes interconnecting these units and connecting them with the usual compressor, a heat pump system is provided which is highly efficient, economically manufactured, and readily serviced.

It is an object of this invention to provide a heat pump having a combination of gaseous and liquid heat exchangers together with capillary connections between said heat exchangers and the usual compressor forming a highly efficient heat pump system.

It is another object of the invention to provide a heat pump having a gaseous heat exchanger which comprises a substantially continuous coil of finned tubing the coil being generally hourglass form, said coil being surrounded by a cylindrical housing and provided with a baffle plate between the smallest diameter coils of the hourglass form so that the air flow through the coil is substantially uniform over the entire area thereof and the velocity of the air is substantially constant.

It is another object of the invention to provide such a gaseous heat exchanger in which the flow of refrigerant medium may be reversed so that the device acts both as an effective collector of liquid refrigerant when utilized as a condenser during the heating function and as an effective refrigerant expansion device when utilized as an evaporator during the cooling function.

It is a still further object of the invention to provide a liquid heat exchanger in which the direction of flow of refrigerant medium may be reversed so the device acts

2

as a condenser during the cooling function and as an evaporator during the heating function.

It is a further object of the invention to provide a liquid heat exchanger particularly adapted for use in a heat pump which heat exchanger comprises a plurality of small tubes located in a particular pattern within a larger tube, the refrigerant medium circulating through the smaller tubes and the cooling or heating water circulating within the larger tube and surrounding the smaller tubes.

It is still another object of the invention is to provide a liquid heat exchanger in which the refrigerant medium is circulated through the small inner tubes in order to prevent damage due to freezing.

Other objects and features of the invention will be apparent when the following description is considered in connection with the annexed drawings, in which,

Figure 1 is a schematic diagram showing a heat pump system in accordance with the present invention;

Figure 2 is a vertical cross-section through a physical embodiment of the heat pump arrangement of Figure 1;

Figure 3 is a horizontal cross-sectional view of the device of Figure 2 the section being taken on the plane of the line 3—3 of Figure 2;

Figure 4 is a perspective view showing a suitable cabinet in which the operating parts of Figure 2 are mounted; and

Figure 5 is a perspective view showing the structural arrangement of the gaseous heat exchanger or evaporator-condenser, the liquid heat exchanger or condenser-evaporator and the compressor devices being mounted together so that they may be treated as a single unit for installation in the cabinet of Figure 4 and for removal for servicing or other purpose.

Referring now to the drawings, there is shown at 10 a gaseous heat exchanger which comprises a coil tubing 11 made up of the lower section 12 which is helically wound to form a conical frustum and the upper section 13 which is wound to form a similar conical frustum which is inverted and mounted upon the lower coil 12. As seen in Figure 2, the coil sections 12 and 13 are preferably formed of two coils which are wound in a parallel arrangement being joined both at the bottom and the top by means of the headers 14 and 15 respectively.

The lower coil section 12 rests upon a plate 16 which has a central circular opening 17 therein to provide for the upward passage of air, the edges of the hole being bent upwardly as are the outer edges of the plate 16 forming a pan for the collection of condensed moisture. The plate 16 is preferably slightly deformed where the coils rest upon it so that it conforms to the helical shape of the coil forming a better support for the coil.

A similar plate 18 is fitted closely to the top of the upper coil section 13 and the outer edges of this plate are joined to or made integral with a cylindrical housing 20 which extends downwardly surrounding the coil sections 12 and 13 and being joined at its bottom portion to the lower plate 16. The cylinder 20 is spaced from the coil sections 12 and 13 to form an air passage between the coils and the inner walls of the cylinder.

Between the two coil sections 12 and 13 there is placed a baffle plate 21 which is circular and which is deformed in the horizontal plane so as to conform to the helical arrangement of the coil sections.

The coil 10 is thus formed into what may be termed an hourglass shape which shape together with the baffle above described provides for an air flow upwardly through the center of the lower section 12, radially outward over the finned tubing comprising the section 12 into the space between the tubing of that section and the casing 20, thence vertically upward, thence radially inwardly and again upwardly through the center of coil section 13 and out through the center of the upper plate 18.

As is readily seen by reference to Figure 2 the air passes over two rows of tubes of the bottom section 12 and then over two rows in the top section 13 thus giving the effect of a four row evaporator.

Since for best efficiency the air flow through a heat exchanger must be uniform over the entire area and since the shape of the evaporator just above-described is such as to produce the necessary changes in the direction of

air flow without the use of deflectors or vanes and at a constant velocity over the entire area, there is produced a simple evaporator which meets the conditions necessary for greatest efficiency. Additionally, the gaseous heat exchanger comprising the finned tubing arranged in a continuous helical form eliminates the return bends generally required in the usual form of evaporator in which straight lengths of tubing are employed, thus eliminating many soldered joints and making the device cheaper to build and more effective since the entire length of the tubing is finned and is effective for heat transfer and the continuous form of the coils effects a minimum of pressure drop during flow of refrigerant through the tubes.

As has been stated, a header 14 joins the parallel coils of the section 12 at the bottom and forms an effective collector of liquid refrigerant when the device is used as a condenser during the heating function. Extending through the header 14, are small liquid distributing tubes 23 terminating in nozzles which extend into the ends of the individual pipes of the lower coil section 12. These nozzles serve to inject liquid refrigerant into the tubes when the coil 10 is used as an evaporator during the cooling function.

The upper header 15 joins the two or more pipes which form the upper coil section 13 and is connected by means of a pipe 24 to a valve 25. The valve 25 is shown in the present instance as a double piston slide valve. When the valve is in the position shown in Figure 1 pipe 24 connects to the pressure side of the compressor 26 and when the valve is moved to the other position as shown in dotted lines in Figure 1, pipe 24 is connected to the suction side of compressor 26.

The condenser-evaporator or liquid heat exchanger of the present invention is shown in Figures 1 and 2. It consists of a helically formed relatively large outer tube 27 having a water outlet provided near its upper end as shown at 28 and a water inlet provided near its lower end shown at 30. The tube 27 has a header 31 at its upper end and a similar header 32 at its lower end. Within the tube 27 there are placed seven small tubes 33 which tubes are arranged in the pattern shown particularly in Figures 1 and 2, that is, one tube being located on the axis of the large tube 27, the others being equally spaced in a circular form around the small central tube. These tubes 33 are fixed in the header plates 31 and 32.

At the lower end of the large outer tube 27 a chamber is formed as is shown in Figure 1, the chamber being separated from the remainder of the tube by means of the header 32 previously described. Extending through the outer walls of this chamber are seven small tubes 34 which tubes extend into the lower ends of the tubes 33 and are tapered forming nozzles there being annular spaces left between the nozzles and the walls of the small tubes 33.

In a similar manner a chamber is formed at the upper end of the tube 27 by means of the header 31 this chamber being connected by means of the pipe 35 to the valve 25 so that it may be connected through that valve either to the suction or compression side of the compressor 26. When the liquid heat exchanger is operating as an evaporator liquid refrigerant collects in the enlarged tube section 36 and is injected through the nozzles 34 into the tubes 33.

It will be noted that the tube 27 has an enlarged diameter at each end as indicated at 37 and 38; the headers 31 and 32 being placed in these large end sections and the water connections being also placed in the enlarged end sections at points close to the header plates in order to permit easy entrance and discharge of water to and from the condenser-evaporator unit.

It will be understood that it has been old to utilize a structure comprising a plurality of small tubes within a large tube. However, in all prior structures the water has circulated within the smaller tubes whereas in the present structure the water circulates in the large tube and the refrigerant within the small tubes. When used as a heat pump it is absolutely necessary that the refrigerant rather than the water circulate within the small tubes in order to prevent damage due to freezing. It is well known as a result of experience with water chillers that when water is circulated in small tubes surrounded by cold refrigerant any reduction in water circulation below a certain minimum while the refrigerant temperature is below 32° F. will cause the formation of ice crystals within the small tube which will then result in reduced water flow and eventually in expansion and bursting of

the small inner tubes. On the other hand, when the small tubes contain refrigerant, upon reduced flow in the outer tube ice crystals will be produced building outwardly on the exterior walls of the small tubes and consequently neither the inner tubes nor the outer tube will burst.

The arrangement of the small tubes 33 within the outer tube 27 is a considerable factor in securing the desired results. The important factors in arranging these tubes are the area of the surface exposed to the refrigerant and the velocity of the circulating liquid. The optimum arrangement with respect to exposed surface is that which offers the maximum surface exposed to refrigerant in the smaller tubes while maintaining the velocity of the liquid sufficiently high to break down the surface film and provide for effective heat transfer from the copper surface to the liquid. The arrangement must, moreover, be such that it will remain fairly constant while the entire assemblage is formed into a coil and it must be such that proper water velocity will be secured together with an adequate flow of water. The arrangement disclosed provides a maximum of inside surface of the small tubes for proper heat exchange from the refrigerant gas to the copper and an adequate area for water flow around the tubes while at the same time providing sufficient velocity to break down the surface film and provide the maximum heat transfer from the copper to the water.

As is clearly shown in Figure 1, the refrigerant gas is condensed and collected in the header 14, flows through the check valve 38, strainer 40, pipe 41, capillary 42 and is discharged through the nozzles 34 into the seven small tubes 33 of the condenser chiller.

The capillary tube 42 provides friction which lowers the pressure of the refrigerant liquid so that when it is discharged through the nozzles it is at the pressure required to boil off or evaporate producing refrigeration and chilling of the water which is circulating through the unit 27.

As will be clear under the conditions discussed above the hot gas is being forced through the pipe 24 by the compressor 26 and through the evaporator-condenser 10 and the air flowing through the coils of that evaporator-condenser is being heated. At this time also the gas flowing through the tubes 33 of the liquid heat exchanger 27 is returned by means of pipe 35 to the suction side of the compressor 26.

When the valve 25 is operated to the position indicated in dotted lines in Figure 1, gas from the compressor flows to the top of the liquid heat exchanger 27, is condensed as it flows through the small pipes 33 due to the chilling effect of the water and the condensed liquid then settles in the bottom of the lower end chamber flowing through the check valve 43, strainer 44, pipe 45, and capillary 46 to the nozzles 23 in header 14. Thus the liquid is injected into the evaporator-condenser 10 and expands therein the gas being returned through check valve 47 and pipes 24 and 24a to the suction side of the compressor. The capillary tube 46 serves in the same manner as does the capillary tube 42 to lower the pressure of the refrigerant liquid so that when it is discharged through the nozzles 23 it is at the pressure required to evaporate.

As is readily seen from the above description when the piston of valve 25 is in one of its two positions, namely, the full line position as seen in Figure 1, the system serves to warm the air passing through the coil 10 whereas when the valve is in its dotted line position the system serves to cool the air passing through that coil.

The various elements heretofore described are assembled in a cabinet 49 such as that shown in Figure 4, this cabinet having an opening 50 in the side thereof and a second opening 51 in the top thereof. Coil 10 on its mounting plate 16 is mounted on a base plate 52 by means of posts 53. The compressor 26 and the condenser-evaporator 27 are also mounted on the base plate 52, the entire unit thus assembled is inserted into the opening 50 in cabinet 49, and a cover member 54 best shown in Figure 2 is positioned over the opening 50. Fixed in the cover plate 54 is a filter member 55 together with the air directing louvers 56.

Mounted in the upper part of the cabinet 49 is a blower 57, of any usual form, discharging through the opening 51, the blower being driven by a motor 58 suitably mounted adjacent the blower in the upper part of the cabinet. As is readily seen, as thus assembled, the device is compact, readily removed from its cabinet

for servicing and as has been described, a unit of high efficiency.

While I have described preferred embodiments of my invention it will be understood that many other modifications may be made without deviating from the principles thereof; therefore I wish to be limited not by the foregoing description, but solely by the claims granted to me.

What is claimed is:

1. A gaseous heat exchanger comprising, in combination, at least one coil of tubing, said coil comprising two sections, each section being wound in generally helical form and forming a truncated cone, the smaller diameter ends of said sections being connected together, a baffle plate intermediate said coil sections and a casing surrounding said coil sections being substantially of the diameter of the large end of said coil sections, said casing having central openings in the ends thereof whereby air is admitted to the center of said lower coil section, flows radially outwardly over said coil, upwardly through said casing, radially inwardly through the turns of the second coil section and outwardly and axially through the opposite central opening in said casing end.

2. A device as claimed in claim 1, characterized in that each coil section is comprised of at least two coils in parallel arrangement forming conical frustums, and further characterized in that the two parallel coils are connected together at their ends by means of headers.

3. A device as claimed in claim 2, characterized in that means are provided in one of said headers for injecting liquid refrigerant into said coils, said means comprising nozzles extending through said header and into the terminal ends of said coils.

4. In a heat pump, a compressor, a gaseous heat exchanger, said gaseous heat exchanger comprising a coil of hourglass shape having a casing of substantially the same diameter as the ends of the hourglass form and having a baffle at the point of narrowest diameter of the hourglass coil to compel air to flow through said hourglass coil at substantially constant velocity, a liquid heat exchanger comprising a large diameter coil through which water is circulated, said large diameter coil having a plurality of small diameter coils therein for circulation of refrigerant, said coils terminating in header plates adjacent the ends of said large diameter coil, valve means positionable to connect the high pressure side of said compressor to one end of said gaseous heat exchanger and the low pressure side to one end of the liquid heat exchanger or to connect the high pressure side of said compressor to the said one end of said liquid heat exchanger, and the low pressure side of said compressor to said one end of said gaseous heat exchanger, nozzles extending into said small tubes of said liquid heat exchanger at the other end thereof, nozzles extending into the tubes of said gaseous heat exchanger

at the other end thereof, means connecting said other end of said gaseous heat exchanger to said nozzles of said liquid heat exchanger, said means including capillary tubing and a check valve, and means connecting said other end of said liquid heat exchanger with said nozzles of said gaseous heat exchanger, said means including capillary tubing and a check valve whereby operation of said valve means serves to reverse the flow of refrigerant through said system and interchange the functions of said liquid and gaseous heat exchangers, said gaseous heat exchanger serving as an evaporator to chill the air flowing therethrough in one position of said valve means and as a condenser to warm the air flowing therethrough in the other position of said valve means.

5. In a liquid heat exchanger for a heat pump system comprising, in combination, a tube of relatively large diameter formed into a helix and having a header at either end forming chambers thereat, seven tubes of smaller diameter within said large tube, one of said seven tubes lying on the helical axis of said large tube and the remaining six of said seven tubes having their axes extending parallel to the axis of said large tube and arranged about said first small tube so that their centers lie equidistant on the circumference of a circle whose center is on the axis of said large tube, the relative size of said large tube and said small tubes being such that each small tube lies closely adjacent to the small central tube and the small tubes on either side thereof, all of said seven small tubes extending between said headers and establishing communication between said headers, means for admitting water to said large diameter tube adjacent one end of the space between said headers, means for withdrawing water from said large diameter tube from the other end of the space between said headers, separate connections to said chambers and nozzle means for delivering a liquid refrigerant directly into said small tubes at one end, said nozzles being of less external diameter than the internal diameter of the small tubes with which they are associated to leave an annular space around said nozzles.
